UNITED STATES PATENT OFFICE.

GEORGE M. FITE, OF NEWHALL, WEST VIRGINIA.

CAR.

1,367,365.

Specification of Letters Patent.

Patented Feb. 1, 1921.

Application filed February 14, 1919. Serial No. 277,004.

To all whom it may concern:

Be it known that I, GEORGE M. FITE, a citizen of the United States, residing at Newhall, in the county of McDowell and State 5 of West Virginia, have invented new and useful Improvements in Cars, of which the following is a specification.

This invention has reference to a slate dump car for coal mines.

10 The object of the invention is to produce a slate dump car which can be arranged in close quarters in a mine without interfering with the passage of the regular coal cars, and which may be readily dumped to remove 15 slate therefrom, so that an accumulation of slate may be deposited any required place or places in or near the mine.

Other objects and advantages will present themselves as the nature of the invention is better understood, reference being had to the accompanying drawings, in which:

Figure 1 is a side elevation of the improvement.

25 Fig. 2 is a top plan view thereof.

Fig. 3 is an end elevation.

Fig. 4 is a sectional view approximately on the line 4—4 of Fig. 1.

30 My improvement includes a frame which includes sills 1 having longitudinal beams 2 secured to the under face thereof, the latter being provided with bearings 3 for the shafts 4 on which are secured flanged wheels 5 that travel on rails 6 of a spur track. Each sill 35 1, at one of the ends thereof is provided with uprights 7, and secured to the top 7' of the said uprights are angularly disposed brace rods 8, connecting the uprights 7 with the sills 1. Preferably the connections between the brace members and the uprights 40 are adjustable, the rods 8 having threaded ends which are engaged by nuts 9.

The lower ends of the brace rods 8 are secured to the projecting ends of what I will 45 term the outer beam 2, while pivotally secured, as at 10 to the sills are track rails 11. By reference to the drawings it will be noted that the track rails 11 are pivoted adjacent to the inner ends thereof and the said 50 inner ends are curved or rounded upon themselves as indicated by the numerals 12. The rails 11 are so spaced as to be arranged between the sills 1, so that the said rails may swing therebetween. The outer end of the 55 rails rest on and extend beyond the beam 24 that is connected between the front ends of

the sills 1. The rails 11 are retained in proper spaced relation with each other by both transverse and diagonal braces 13 and 14 respectively. The rails 11 are designed to receive a slate dump car 15, and it will be apparent that when the said car is wheeled to bring one end thereof into contacting engagement with the curved inner end of the rails 11, the said car and rails may be swung upon the pivots 10 so that the contents of the car 15 may be dumped therefrom.

Journalized in suitable bearings at what I have termed the outer end of the sills 1 is a transverse shaft 16. Around this shaft and secured thereto is a chain 17, the said chain having a hook at the free end thereof which engages in an eye 18 in the outer transverse connecting bar between the rails 11. Secured on one end of the shaft 16 is a toothed wheel 19 engaged by a dog 20 on the beam 2. Straddling the toothed wheel 19 and loosely arranged on the shaft 16 is the bifurcated end 21 of an operating lever 22. This lever is provided with a spring pressed pawl 23 that engages with the toothed wheel, so that the shaft can be revolved when the lever is actuated in one direction. By releasing the dog 20 and the pawl 23 the car, when brought to the position above referred to 75 will be permitted to dump automatically. By operating the lever the track and car will be brought to their initial position.

With my improvement the rear or dumping end of the frame is open so that the slate 90 from the car will properly pass therefrom between the sills to the uprights 7 at the rear end of the frame. The top member 7' serves as a stop for preventing the car being thrown off the frame, while the curved ends 12 of 95 the rails hold the outer wheels of the car thereon. The top beams 7' as well as the uprights 7 are effectively supported by the diagonal braces 8.

The track provided by the rails 11 is of a 100 width similar to that of the track 11^a in the mine and the car is loaded in the mine with slate or other debris and is run out of the mine to a point where it is placed on the track rails 11 of the improvement. The 105 wheeled frame car is then moved on the spur track rails 6 to a point where the waste material is to be unloaded and the car is then dumped. From experience, I have found that with my improvement, two men can do 110 as much work in handling slate or debris as usually requires a large number when such

materials are conveyed by hand. When the car of waste or slate is brought out to where the side dump car is on the track it is so arranged that the spur track is perhaps two 5 or two and one-half feet lower, and the loaded car is placed upon the dump car and the same power is used as is employed at the car mine for moving the dump car. The spur track is made as much lower than the 10 mine track as the side dump car is higher. The advantage gained by reason of the side dump car is that the same may be unloaded anywhere along the spur track and when an entire space has been filled along the side 15 of the spur track only a short time is required to set the track over and the waste material may be employed for increasing the yardage, which, of course, is highly desirable.

Having thus described the invention, what is claimed as new, is:-

1. In a side dump apparatus for slate or waste cars for coal mines, the combination of a main track for the mine car and a spur 25 track at the end of the main track positioned therebelow and at an angle thereto; of a side dump car movable on the spur track, pivotally supported rails on the dump car having ends designed for registering alignment 30 with the ends of the rails of the main track when the dump car is brought opposite the main track to receive a loaded mine car from the main track, and the said mine car, when on the rails of the dump car designed by the weight thereof to swing said 35 rails and to bring the mine car to dumping position, means for holding the mine car on the said rails when in dumping position,

means for returning the rails of the dump car to normal position to permit of the mine 40 car being moved off of the said rails on to the rails of the main track, and said means also operable for holding the rails of the dump car from tilting either before or after the mine car is arranged thereon. 45

2. In a side dump apparatus for slate or waste cars for coal mines, the combination of a main track on which the mine car travels, a spur track at the terminal of the main track arranged therebelow and at an angle 50 with respect thereto; of a side dump car traveling on the spur track, transverse sills on the body of the car, uprights on the outer ends of the sills, a connecting member for the uprights, angle braces between the uprights and the body of the dump car, a track comprising two spaced rails, disposed between the sills and having their outer ends rounded upwardly, and the said rails being pivotally supported between the sills, means 55 for retaining the rails in a position whereby the same will aline with the rails of the main track so that a mine car from the main track may be moved on to the rails of the dump car, and the said mine car, when arranged on 60 the dump car designed, by virtue of the weight thereof to tilt the rails of the dump car to bring the mine car to dumping position, lever operated means for returning the rails and dump car to initial position for 65 permitting the dump car to again be moved on to the rails of the main track, and said means also designed for retaining the rails of the dump car in normal initial position.

In testimony whereof I affix my signature. 70
GEORGE M. FITE. 75
